THERMOSTATIC SWITCH

John D. Bolesky, Mansfield, Ohio, assignor, by
mesne assignments, to Adrian Medert, Cleve-
land, Ohio, and Russell W. Bolesky, Mansfield,
Ohio, as trustees

Application October 13, 1948, Serial No. 54,280

14 Claims. (Cl. 200—138.)

1

This invention relates to thermostatic circuit breakers, and more particularly to thermostatically controlled switches and the like.

It is among the objects of the present invention to provide a new and novel thermostatically controlled switch which is adapted to interrupt or open an electric circuit automatically on a rise of temperature to a predetermined point and requiring manual actuation to close the circuit after it has been so opened.

Another object of the invention is to provide in a thermal responsive device a thermal element having two positions of concavity, which element is free to pass automatically from its first position to its second position upon a change in temperature and is caused to actuate a switch in its second position and is free to return to its first position upon a subsequent change in temperature.

Another object of my invention is the provision of a manual reset thermostatic switch of this character wherein the switch mechanism is trip-free of the manual reset lever.

A further object of my invention is the provision of a resetting mechanism for a thermostatic device of the class described wherein the reset lever serves as an indicator of the position of the switch within the device.

A still further object of the invention is to provide a thermal responsive device having a switch member for controlling a circuit through the device actuated by a thermal element having two positions of concavity which element is free to pass automatically from its opposed positions of concavity and is caused to actuate the switch to open the circuit in one of said positions and manually operable mechanism for securing the switch in circuit open position.

A still further object of the invention is to provide a thermal responsive device having a manually actuated member for resetting a switch controlling a circuit through the device wherein the switch is free to open and close the circuit in the event the reset member becomes inoperable.

A further object of the invention is to provide a thermal responsive device embodying switch means arranged to control a plurality of circuits through the device.

It is a still further object of this invention to provide a thermostatic switch device of the class described which because of its simplicity, economy of construction and reliability and efficiency of operation is particularly adapted as a protective device in controlling circuits wherein the current is employed for heating purposes.

2

These and other objects and advantageous features of the invention not at this time more particularly pointed out will become more apparent as the nature of the invention is better understood from the following detailed description taken in conjunction with the accompanying drawings wherein like reference characters denote corresponding parts, and wherein:

Figure 1 is a front elevational view of a thermostatic control device embodying the present invention;

Figure 2 is a side elevational view of the device of Figure 1;

Figure 3 is a rear view of the device shown in Figure 1 with the thermostatic element removed;

Figures 4 and 5 are sectional views taken on the lines 4—4 and 5—5, respectively of Figure 3;

Figures 6 and 7 are enlarged longitudinal medial sectional views taken on the line 6—6 of Figure 1 illustrating the elements of the device in circuit closing and circuit opening position respectively;

Figure 8 is a rear plan view of the device similar to Figure 3 with the thermoelement in operative position; and

Figure 9 is a schematic electrical circuit diagram illustrating the device of the present invention applied to apparatus embodying a thermostatically controlled electrical heating element.

With reference to the accompanying drawing there is illustrated a thermostatically controlled device embodying a switch for controlling an electrical circuit made in accordance with the present invention and comprising a substantially rectangular housing 10 having laterally outwardly extending ears 11 and 12 formed on the opposed ends thereof suitably apertured as at 13 to receive screws or other securing means (not shown) for attaching the device to a suitable support or to the apparatus with which it is to function. The housing 10 is preferably made of an electrical insulating material which is heat resistant to a fair degree, such as a phenolic condensation product or the like. The face 15 of the housing 10 is formed with a transverse upstanding boss 16, intermediate the extremities of which there are provided lateral projections 17. One end of the boss 16 is notched or cut away to a point below the face 15 to provide a slot 18, the purpose of which will appear hereinafter.

The housing 10 is open at the rear thereof and the interior of the housing is divided into three sections 20, 21 and 22 by means of upstanding transverse walls 23 and 24 in which are formed

opposed slots 25 midway between the extremities thereof. The sections 20 and 22 are similarly formed each having a centrally positioned substantially rectangular depressed portion 26 in which there is provided a bore 27 extending into the body portion of the lateral projections 17. Mounted in the bore 27 is a coil spring 29, one end of which bears against the base of the bore 27 and the other against the lower surface of a bridging contact 30 seated within the depressed portion 26 and substantially filling the same. Adjacent each end of the sections 20 and 22 there is formed an aperture 28 the outer end of which is countersunk to receive the head of a terminal post 31 mounted in the aperture. Each of the posts 31 is provided with a threaded bore adapted to receive the usual binding post 32 to which lead wires are secured. Secured to the inner ends of each of the terminal posts 31 are contact elements 33 seated within the ends of the sections 20 and 22 and arranged to overlie and be engaged by the bridging contact 30.

The central section 21 of the interior of the housing 10 is depressed into the boss 16 below the outer surface of the face of the housing and receives therewithin a longitudinally slidable reset arm 35 (see Figures 3 and 5) the outer end of which projects through the housing 10 into the slot 18 and may be extended beyond the side of the housing 10. The reset arm 35 is provided with an elongated slot 36 the outer portion 37 thereof being of greater width and defining a shoulder 38. The inner end of the reset arm 35 is formed with an upstanding lug or flange 39 through which extends an aperture 40. The housing section 21 is provided with spaced apertures 41 and 42 extending through the face of the housing 10. Mounted in the apertures 41 and 42 are rivets 43 and 44, respectively, which project through the elongated slot 36 of the reset arm 35 and are provided with heads which overlie the reset arm 35 and retain it in slidable position within the section 21. Shouldered portions formed on the rivets 43 and 44 below the heads thereof permit the free reciprocation of the reset arm 35 within the housing section 21. The rivet 44 is extended beyond the head thereof to form an upstanding post 45. Extending between aperture 40 in the flange 39 and the post 45 is a spring 46 which serves to normally urge the reset arm 35 outwardly and project the end thereof beyond the wall of the housing 10.

For moving the bridging contact 30 out of engagement with the adjacent contact elements 33 and thereby breaking the circuit thereto there is provided contact actuator 50, which similar to the housing 10, is made of electrical insulating material. As best shown in Figures 3 and 6 of the drawings the contact actuator 50 comprises a body portion 51 substantially square in cross-section and formed with outwardly extending feet members 52 the outer extremities of which are adapted to engage the upper surface of the bridging contacts 30 in each of the sections 20 and 22. Pressed into a slot 53 extending into the interior of the body 51 is a catch member 54 provided with serrated edge portions 55 which serve to prevent the withdrawal of the member 54 from the slot 53. The member 54 is provided with an elongated opening 56 through which the wire connecting the spring 46 to the post 45 is adapted to pass. Inwardly extending opposed slots 57 are formed in the edge portions of the catch member 54 adjacent the lower extremity thereof. When

the contact actuator 50 is mounted in the section 21 the lower end of the catch member 54 is adapted to extend into a suitable recess 58 of a predetermined depth formed in the lower surface of central section 21 which serves to guide and limit the downward movement of the contact actuator. When the reset arm 35 is disposed in its innermost position the lower extremity of the member 54 is freely movable through the portion 37 of the slot 36 formed in the reset arm 35. When the member 35 is projected outwardly the edge portions of the slot 36 at its narrow extremity are received within the cutaway portions 57 in the member 54 (see Figure 7) thereby preventing the member 54 and the contact actuator 50 to which it is secured, from moving upwardly in response to the pressure of the springs 29 upon the bridging contacts 30 bearing against the feet member 52 of the contact actuator 50 after it has been moved to such position as hereinafter described.

On the upper surface of the contact actuator member 50 there is provided a bumper button 60 which is adapted to be engaged by a composite thermostatic plate 61. The thermostatic plate 61 may be a dished bimetallic snap-acting thermostatic element being characterized in that its central portion has one position of stable equilibrium when it is cold and another relatively stable position of equilibrium when it is hot, the hot and cold positions having opposite curvatures. As illustrated in Figure 6 the thermostatic element 61 is shown when the same is cold having an outward curvature, and in Figure 7 the element is illustrated in the position taken when it is hot, being curved inwardly and engaging the bumper button 60. The thermostatic plate 61 is circular and the edge thereof is adapted to be received within shouldered portions 62 of the housing 10 adjacent the ears 11. A mounting plate 63 having a configuration complementary to the rear surface of the housing 10 and formed with a peripheral flange 64 which engages the side of the housing 10 thereabout serves to maintain the plate 61 on the rear face of the housing 10. Ears 65 formed integrally with the flange 64 of a length to extend beyond the thickness of the ears 11 are adapted to be bent thereover to hold the mounting plate 63 in position. The mounting plate 63 is provided with a circular opening 66 the edge portion of which overlaps and confines the edge of the thermal plate 61. The central portion of plate 61 freely moves between its positions of opposite concavity in response to changes in temperature and serves to move the contact actuator as it moves from its first position of concavity as shown in Figure 6 to its second position as shown in Figure 7.

The thermostatically controlled switch of the present invention is particularly adaptable for use with apparatus employing electric current for heating purposes, serving to interrupt the circuit when the temperature of the device reaches a predetermined degree. The thermostatic switch in such cases may serve as a safety device in the event that the normal controlling devices fail to function properly thereby preventing overheating and damage to the apparatus. With reference to Figure 9 of the drawings the thermostatic control device of my invention is schematically illustrated in the circuit of a heating element which may be incorporated in apparatus such as a water heater. The numerals 70 and 71 designate power lines and numerals 72 and 73 indicate diagrammatically a thermostat and a heater, respectively.

A conductor 74 connects the power line 70 to one terminal 32 of one switch of the device "A." A conductor 75 connects the other terminal 32 to one terminal of the thermostat 72 which in turn is connected to heater element 73 by conductor 76. A conductor 77 leads from the heater element 73 to the terminal 32 of the second switch of the device "A" which is connected to the other power line 71 by conductor 78. Tracing the circuit with the switches of the device "A" closed it will be seen that power passes from the supply line 70 through conductor 74 to terminal 32, contact element 33, across bridging contact 30 to the other contact element 33 thence out through the terminal 32 connected thereto, conductor 75 to terminal 80 of thermostat 72, through thermostat 72 to terminal 81, thence through conductor 16 to terminal 82 of heater element 73, through heater element 72 to terminal 83, thence through conductor 77 to terminal 32 of the second switch of the device "A," contact element 33, across bridging contact 30 to other contact element 33, out through terminal 32 connected thereto and thence through conductor 78 to power line 71. The elements of the device "A" when in this position are illustrated in Figure 6 of the drawings. Upon the occurrence of a temperature condition of a predetermined degree causing a rise in the temperature of the thermostatic plate 61 above its stable position as shown in Figure 6, it snaps into the position shown in Figure 7 in which the concavity of the plate 61 is opposite to that shown in Figure 6. When the thermostatic element 61 snaps into this position, the center thereof engages the bumper button 60 on the contact actuator 50 moving the same downwardly. Movement of the contact element downwardly moves the bridging element 30 out of engagement with its adjacent contact elements 33 thereby breaking the electrical circuit. Movement of the contact actuator 50 downwardly brings the slotted portion of the element 54 into registry with the slot 36 in the reset arm 35 thereby permitting the arm 35 to be moved outwardly in response to the action of the spring 46. The outer end of the arm 35 is thus projected beyond the wall of the housing 10 as shown in dotted lines in Figure 3 and when so positioned indicates that the contacts of the switch are open and the circuit broken. As shown in Figure 7, the lower extremity of the member 54 is locked beneath the reset arm 35 when the same is in its extended position thereby holding the bridging element 30 from engagement with the contact elements 33 upon movement of the thermostatic element 61 to its initial position shown in Figure 6. The circuit, after being opened automatically by a rise in temperature to a predetermined point, cannot be closed until the reset arm 35 is moved manually inwardly. Upon such movement the catch member 54 is released by the arm 35 permitting the contact actuator 50 to be moved upwardly in response to pressure of the springs 29 which close the circuit across contacts 33 through bridging element 30. It is to be noted that if the reset arm 35 fails or is prevented from moving outwardly and thereby latching the contact actuator in switch open position the device will still operate to open the circuit. The contact actuator will, in such case, follow the thermostatic plate 61 as it automatically snaps from one position of concavity to its opposite position in response to temperature changes and will open and close the circuit through the device. Thus the action of the thermostatic plate is free from the switch and the

switch is always opened when the thermostatic plate moves into its second position of concavity.

Having thus described my invention so that persons skilled in the art may understand and practice the same, what I desire to obtain by Letters Patent is embodied in the appended claims.

I claim:

1. A thermostatic control device comprising a housing, an electric switch within said housing including a plurality of stationary contacts and a contact movable into and out of contact with said stationary contacts, a contact actuator member engageable with said movable contact, a snap acting thermostatic plate having its peripheral edge portion confined in said housing, said thermostatic plate having two oppositely facing positions of stability in one of which positions its central portion is adapted to engage and act against said actuator member and simultaneously open all of the contacts of said switch, manually operable means movable relative to said actuator member, and spring means urging said manual means to an extended position exterior of said housing, said manual means serving to maintain said actuator member in switch opening position upon movement thereof to its extended position.
2. A thermostatic control device comprising a housing, an electric switch within said housing, a contact actuator member movable to open said switch, a snap acting thermostatic plate peripherally mounted on said housing and having two positions of stability, said thermostatic plate passing automatically from its first position to its second position of stability upon change of temperature to a predetermined degree, said thermostatic plate in its second position adapted to have its central portion engage and move said contact actuator and open said switch, means engageable with said contact actuator for maintaining the same in open switch position, and manual means for releasing said contact actuator and permitting the switch to close.
3. A thermostatic control device comprising a housing, an electric switch within said housing, a contact actuator member movable to open said switch, a snap acting thermostatic plate having its peripheral edge portion confined in said housing and having two positions of stability, said thermostatic plate passing automatically from its first position to its second position of stability upon change of temperature to a predetermined degree, the central portion of said thermostatic plate in its second position adapted to engage and move said contact actuator and open said switch, and means engageable with said contact actuator for maintaining the same in open switch position, said means including a slidable lever and spring means for urging said lever to an extended position exterior of said housing.
4. A thermostatic control device comprising a housing, an electric switch within said housing, a contact actuator member movable to open said switch, a snap acting thermostatic disc having its peripheral edge portion confined in said housing and having two positions of stability, said thermostatic disc passing automatically from its first position to its second position of stability upon change of temperature to a predetermined degree, said thermostatic disc in its second position adapted to engage and move said contact actuator and open said switch, and means for maintaining said contact actuator in switch open position, said means including a slidable member normally under spring tension adapted to move into

engagement with said contact actuator and retain the contact actuator against return movement irrespective of the position of the thermostatic plate.

5. A thermostatic control device comprising a housing, an electric switch within said housing, a contact actuator member movable to open said switch, a snap acting thermostatic plate having its peripheral edge confined in said housing having two positions of stability and arranged to pass automatically from its first position to its second position of stability upon change of temperature to a predetermined degree, the central portion of said thermostatic plate upon moving to said second position adapted to engage and move the contact actuator and open said switch, and means operable independently of said thermostatic plate upon said contact actuator for securing the same in open switch position.

6. A thermostatic control device comprising a housing, an electric switch within said housing including a plurality of stationary contacts and a contact movable into and out of contact with said stationary contacts, a contact actuator member engageable with said movable contact, a snap acting thermostatic plate having its peripheral edge portion confined in said housing and having two positions of stability, said thermostatic plate passing automatically from its first position to its second position of stability upon change of temperature to a predetermined degree and upon such movement the central portion thereof is adapted to engage the contact actuator member and simultaneously open the contacts of said switch, manually operable means movable relative to said contact actuator member, and spring means urging said manual means to an extended position exterior of said housing, said manual means serving to maintain said contact actuator member in switch opening position upon movement thereof to its extended position.

7. A thermostatic control device comprising a housing, an electric switch within said housing including a plurality of stationary contacts and a contact movable into and out of contact with said stationary contacts, a contact actuator member engageable with said movable contact, a snap acting thermostatic plate having its peripheral edge portion confined in said housing and having two positions of stability, said thermostatic plate being free to move automatically from its first position to its second position of stability upon change of temperature to a predetermined degree independently of the switch elements and upon such movement to engage the contact actuator member and simultaneously open all of the contacts of said switch, and manually operable means movable in response to movement of said contact actuator to secure the switch in open position.

8. A thermostatic control device comprising a housing, an electric switch within said housing including a plurality of stationary contacts and a contact movable into and out of contact with said stationary contacts, means for maintaining said stationary and movable contacts in engagement, a contact actuator member engageable with said movable contact, a snap acting thermostatic plate having its peripheral edge portion confined in said housing and having two positions of stability, said thermostatic plate being independent of the said switch and free to pass automatically from its first position to its second position of stability upon change of temperature to a predetermined degree and upon

such movement to engage and move the contact actuator member and open the contacts of said switch, manually operable means responsive to the movement of said contact actuator for securing the switch in open position, and means for releasing the contact actuator and closing the switch.

9. A thermostatic control device comprising a housing, an electric switch within said housing including a plurality of stationary contacts and a contact movable into and out of contact with said stationary contacts, a contact actuator member engageable with said movable contact, a snap acting thermostatic plate having its peripheral edge portion fixedly secured in said housing and its central portion being free to assume positions of opposite concavity in one of which positions it is adapted to act against said contact actuator member and open the contacts of said switch, and means operable upon said contact actuator member for securing the same in open switch position.

10. A thermostatic control device comprising a housing, an electric switch within said housing including a plurality of stationary contacts and a contact movable into and out of contact with said stationary contacts, means for maintaining said stationary and movable contacts in engagement, a contact actuator member engageable with said movable contact, a snap acting thermostatic plate having its peripheral edge portion rigidly secured in said housing and its central portion free to assume positions of opposite concavity in one of which positions it is adapted to engage and act against said contact actuator member and open the contacts of said switch, and means responsive to movement of said contact actuator for securing the switch in open position, said means adapted to be manually actuated to close the switch upon return of said thermostatic plate to its first position.

11. A thermostatic control device comprising a housing, an electric switch within said housing including a plurality of stationary contacts and a contact movable into and out of contact with said stationary contacts to complete a circuit thereacross, a contact actuator member engageable with said movable contact, a snap acting thermostatic plate movable independently of said switch and operably positioned with respect to said contact actuator, said thermostatic plate having its peripheral edge portion confined and its central portion capable of snapping between positions of opposite concavity under changing ambient temperature whereby the contact actuator is caused to open said switch contacts, manually operable means movable relative to said contact actuator member, and spring means urging said manual means to an extended position exterior of said housing, said manual means including means for maintaining said contact actuator member in switch opening position upon movement thereof to its extended position.

12. A thermostatic control device comprising a housing, an electric switch within said housing including a plurality of stationary contacts and a contact movable into and out of contact with said stationary contacts to complete a circuit thereacross, means for maintaining said stationary and movable contacts in engagement, a contact actuator member engageable with said movable contact, a snap acting thermostatic plate freely movable relative to said switch and operably positioned with respect to said contact actuator, said thermostatic plate having its pe-

peripheral edge portion confined and its central portion capable of snapping between positions of opposite concavity under changing ambient temperature and to engage and move the contact actuator to open said switch contacts, a manually operable arm slidably mounted relative to said contact actuator member, and spring means for urging said arm to an extended position exterior of said housing, said arm engageable with said contact actuator member upon movement thereof to its extended position and serving to hold the same in such position irrespective of the position of the thermostatic plate until the arm is manually returned to initial position within the housing.

13. A thermostatic control device comprising a housing, spaced switches mounted within said housing embodying opposed contacts, a contact actuator bridging the space between said switches and movable to open the contacts of said switches, a snap acting thermostatic plate confined at its periphery in said housing with its central portion having two positions of stability, said thermostatic plate passing automatically from its first position to its second position of stability upon change of temperature to a predetermined degree, said thermostatic plate in its second position arranged to have its central portion engage and move said contact actuator and open the contacts of said switches, said contact actuator being adapted to maintain the switches in open position and, manually operated means for re-

leasing said contact actuator and permitting the contacts of said switches to close.

14. A thermostatic control device comprising a housing, spaced switches mounted within said housing embodying opposed contacts, a contact actuator bridging the space between said switches and movable to open the contacts of said switches, a snap acting thermostatic disc confined at its periphery in said housing with its central portion free to assume opposite positions of concavity, said thermostatic disc passing automatically from its first position to its second position of concavity upon change of temperature to a predetermined degree, said thermostatic plate in its second position adapted to have its central portion engage and move said contact actuator to open the contacts of said switches, and manually operable means effective to release said contact actuator and permit the contacts of said switches to close.
